[57] CLAIM

The ornamental design for a snack food product, as shown and described.

DESCRIPTION

FIG. 1 is a top plan view of a snack food product illustrating my new design with the bottom view being a mirror image thereof;

FIG. 2 is a front elevational view thereof; the rear elevational view being a mirror image thereof;

FIG. 3 is an end view thereof with the opposite end being a mirror image thereof;

FIG. 4 is a sectional side view thereof taken along lines 4—4 of FIG. 2 showing an interior cavity containing a filling; and,

FIG. 5 is a sectional view of a second embodiment of FIG. 1, taken along line 4—4 of FIG. 2, it being understood that the only difference in the second embodiment is the empty interior cavity.
